UNITED STATES PATENT OFFICE.

CHARLES E. ONGLEY, OF NEW YORK, N. Y., ASSIGNOR TO THE HYDRAULIC ELEVATOR COMPANY, OF ILLINOIS.

ELEVATOR.

SPECIFICATION forming part of Letters Patent No. 410,181, dated September 3, 1889.

Original application filed November 22, 1887, Serial No. 255,857. Divided and this application filed March 9, 1888. Serial No. 266,653. (No model.)

To all whom it may concern:

Be it known that I, CHARLES E. ONGLEY, a citizen of the United States, residing at New York, county of New York, and State of New York, have invented certain new and useful Improvements in Elevators, fully described and represented in the following specification and the accompanying drawings, forming a part of the same.

10 This invention relates to a mechanism for operating the main valve or other mechanism which controls the movements of an elevator, which is especially adapted for use in connection with a system of electrical connections for operating the same, such as or similar to that shown in my prior application for Letters Patent filed November 22, 1887, Serial No. 255,857, of which application the present is a division. The mechanism constituting the 20 present invention may, however, be operated otherwise than electrically.

The invention consists, primarily, in what I term an "auxiliary-valve apparatus," by which the elevator-controlling mechanism is 25 operated in the ordinary working of the elevator, but which is so constructed and organized as to permit the main valve or other controlling mechanism to be operated by other means in case of an emergency.

30 In the accompanying drawings, Figure 1 is a diagrammatic view illustrating an organization of the apparatus embodying the present invention. Fig. 2 is an enlarged elevation of what I term the "auxiliary-valve apparatus," by which the main valve is moved in one direction; and Fig. 3 is a sectional view of the same.

Referring to said drawings, it is to be understood that B represents an elevator-car, C 40 a hydraulic cylinder or other motor by which the car is raised, and D the hoisting-cable, all of which parts are organized in the usual and well-known manner.

E represents the mechanism for controlling 45 the movements of the elevator, which, in the case shown, is the main or induction and exhaust valve of the cylinder C, and is of any suitable construction to allow the water to be admitted to the cylinder to cause the car to ascend when the valve is in one position, to al-

low the water to escape from the cylinder to permit the car to descend when the valve is reversed, and to close both the induction and exhaust to stop the car when the valve is in an intermediate or mid position. Such cylinders and valves are in common use, and their construction is well known. I have not, therefore, deemed it necessary to illustrate or describe the same in detail. It is to be understood, however, that the cylinder C may, 55 if preferred, be arranged vertically instead of horizontally, and may be provided with the well-known circulating-pipe, or may be a motor of any of the forms common in elevators. The mechanism for controlling the movements of the elevator is therefore the main valve or other mechanism which controls the movements of the elevator-motor, and will vary according to the character of the motor employed. The main valve or other controlling mechanism is connected to the rod F of a piston F', which works in a cylinder F², connected to pipes G G', forming ports, through which water under pressure flows into and out of the cylinder upon the opposite sides of 75 the piston F', thereby moving it and the connected main valve upward or downward, as it is desired to cause the car to descend or ascend. The pipes G G' are controlled by means of auxiliary-valve mechanisms H O, which are 80 operated, preferably, by electromotors under the control of the conductor in the car. As the auxiliary-valve mechanisms H O are connected by the pipes G G' with the valve-operating cylinder F², these mechanisms may 85 be placed in any convenient position in any portion of the building, either near to or remote from the main valve of the elevator.

The auxiliary-valve mechanisms H O are alike in construction and operation, and have 90 for convenience a common water-supply, one apparatus controlling the pipe G and the other the pipe G'. These auxiliary-valve apparatuses are controlled in the case shown by electromotors I J, which are energized through electric circuits, including suitable battery power and appropriate circuit-closers, located upon the car and at the different landings, all as shown and described in my prior application before referred to.

The construction and operation of the auxiliary-valve mechanisms H O will now be described. As these two mechanisms are exact duplicates, a description of one will apply to 5 both.

Referring to Figs. 2 and 3, it is to be understood that *a* is a valve-cylinder containing two valve-seats *c*², formed upon the ends of a bushing *b*, having perforations *c*' and two 10 heads *b'* *b*², which are securely fastened in the cylinder. The auxiliary induction and exhaust valves *d e* are connected by a valve-rod *f*, to which a spiral spring *f'* is applied to hold the valve *d* against its seat and the 15 valve *e* away from its seat. The valve-cylinder is enlarged at one end to form a cylinder *a'*, in which is fitted a piston *g*, which is attached to the valve-rod *f*. Communicating with the cylinder *a'* is a pipe *h*, which is controlled by a valve *h*³, termed for convenience a "primary valve," the rod *h*⁴ of which is adjustably connected by the nuts *j*⁴ to a lever *j*, carrying at its free end an armature *j'*, held within the magnetic field of the electromotor *J* by means of the suspension-rod *j*², having a nut *j*³, by which the position of the lever *j* is adjusted.

The water-supply pipe *k* communicates with the valve-cylinder *a*, and also with the pipe *h*, 30 as shown, and the induction and exhaust pipes *G G'* communicate with the cylinders *a* of the respective valve mechanisms between the heads *b'* *b*² of the bushing *b*. Each of the cylinders *a* is provided with a waste-pipe *l*, 35 which communicates with the space between the valve *e* and piston *g*, and each of the pipes *h* is provided with a small open waste-pipe *m*, which communicates with the pipe between the piston *g* and valve *h*³.

40 The operation is as follows: The valves *d* are normally held against their seats *c*² and the valves *e* away from the seats by the springs *f'*, and also by the pressure of the water in the supply-pipe *k*, thereby preventing any water from entering either of the 45 pipes *G* or *G'* to create a greater pressure upon one side of the piston *F'* and operate the main valve and at the same time leaving the pipes *G G'* open to allow the water to flow 50 out of either end of the cylinder *F'*, and thus permit the piston *F'* to be moved in either direction. As soon, however, as either one of the motors *I* or *J* is energized by the closing of the electric circuit through said motor, its 55 armature will be attracted, thus raising the lever *j* and primary or motor valve *h*³ and allowing water from the pipe *h* to enter the cylinder *a'* and act upon the piston *g*, and as the area of the piston *g* exceeds that of the 60 auxiliary induction-valve *d* the valve *e* will be moved to its seat and the valve *d* away from its seat and allow the water to enter by the valve *d* and pass through the openings *c*' to the pipe *G* or *G'*, as the case may be, and 65 to the cylinder *F'*, causing the piston *F'* to be moved and operate the main valve to cause the car to ascend or descend. As soon as

the circuit through the motor is broken the motor will be de-energized and its armature released. The weight of the lever *j*, 70 aided by the pressure of the water in the pipe *h*, will at once close the primary valve *h*³, thereby removing the pressure from the piston *g*. The water between the valve *h*³ and the piston *g* will then gradually escape through the pipe *m*, thereby allowing the spring *f'* to restore the auxiliary induction and exhaust valves to their normal position. By closing the circuit through the other motor the same operation will take place in the 75 other auxiliary-valve apparatus, thereby admitting water to the other end of the cylinder *F'* to act upon the opposite side of the piston *F'* and move the main valve in the opposite direction, and this being continued the main 80 valve will be reversed and the car caused to move in the opposite direction; or if it is desired to simply stop the car the circuit will be broken as soon as the main valve arrives in its mid-position, and the car will then remain 85 at rest. As the piston *F'* is moved in either direction by the admission of water to one end of the cylinder *F'*, the water in the other end of the cylinder will find an unobstructed escape through the pipe *G* or *G'*, as the case 90 may be, and past the auxiliary exhaust-valve *e* to the waste-pipe *l*. The waste-pipes *m* are, as will be observed, always open for the escape of water from the cylinder *a'*; but these pipes being of small size as compared with 95 the pipes *h*, the water will not escape with sufficient rapidity to prevent the pistons *g* from operating properly.

The rods *h*⁴ of the primary valves *h*³ are 100 preferably provided with sliding joints, as shown in Fig. 3, so as to permit those valves to accommodate themselves more readily to their seats.

Although the valves *h*³ are herein illustrated as provided with means by which they 110 are operated electrically, it is to be understood, as before stated, that these valves may be operated through other suitable connections with the car, if preferred.

In addition to the appliances for controlling the ordinary working movements of the elevator through the auxiliary-valve apparatuses which have been described, it is desirable that means should be provided by which, in case of an accident or in case the auxiliary-valve apparatuses should for any reason 120 become ineffective, the conductor can operate the main valve or other mechanism which controls the movement of the car directly. For this purpose the rod *F* is provided with 125 the usual rack, which is engaged by a pinion upon a shaft 21, having a pulley 20, around which passes a hand-rope 22, which extends around pulleys located at the top and bottom of the shaft and passes through the car in the 130 usual manner.

It has already been stated that the auxiliary induction and exhaust valves *d e* are normally maintained in such position as to

open the pipes G G' to allow the water to flow out of the cylinder from both sides of the piston F', and thus permit the piston to be moved in either direction. From this it results that in case the auxiliary-valve mechanisms fail to act the main valve will not be

5 locked by the water in the cylinder F², but will be free to be operated by the hand-rope 22 or other mechanical connection. This 10 hand-rope will not be used in the ordinary working of the elevator; but in case of any emergency, as before stated, the conductor can, by means of this hand-rope, operate the main valve, and thus have mechanical control 15 of the movements of the elevator, as in the old way.

The hand-rope 22 may be provided with the usual buttons located near the top and bottom of the shaft, and which will engage with 20 the car and operate the main valve to stop the car before it reaches the limit of its movement in either direction. The ordinary hand-rope is herein illustrated as the simplest and, all things considered, the most desirable mechanical appliance for controlling the valve, 25 in connection with the electrical appliances herein described; but it is to be understood that any of the other forms of mechanical connections by which the conductor in the car is 30 enabled to control the main valve may be applied and used in place of the simple hand-rope shown, and are to be regarded in this connection as equivalents of said rope and included within the term "rope."

35 The form of motor C, for operating the elevator, which is herein shown, has been selected merely for the purpose of illustrating one application of the invention. Any other suitable form of motor may of course be employed.

What I claim is—

1. The combination, with the mechanism for controlling the movements of an elevator, of the cylinder F² and piston F', for operating said mechanism, an auxiliary valve for controlling said piston, which is normally maintained in position to allow the water to flow out of the cylinder, a piston for operating said auxiliary valve, and a primary valve for controlling said last piston, substantially as 45 50 described.

2. The combination, with the mechanism for controlling the movements of an elevator, of the cylinder F² and piston F', for operating said mechanism, an auxiliary valve for controlling said piston, which is normally maintained in position to allow the water to flow out of the cylinder, a piston for operating said auxiliary valve, a primary valve for controlling said last piston, and a permanently- 55 60 open exhaust between said last piston and said primary valve, substantially as described.

3. The combination, with the mechanism for controlling the movements of an elevator, of the cylinder F² and piston F', for actuating 65 said mechanism, an auxiliary-valve apparatus controlling said piston and normally maintained in an open position to allow the water to flow out of the cylinder from either side of the piston, pistons for operating said auxiliary-valve apparatus, primary valves for controlling said last pistons, and a rope connected to operate said controlling mechanism from the elevator, substantially as described.

In testimony whereof I have hereunto set 70 75 my hand in the presence of two subscribing witnesses.

CHARLES E. ONGLEY.
